UNITED STATES PATENT OFFICE.

DAVID K. HUTCHCRAFT, OF INDIANAPOLIS, INDIANA, ASSIGNOR TO INDIANA AIR PUMP COMPANY, OF INDIANAPOLIS, INDIANA, A CORPORATION.

AIR-LIFT-PUMP CONTROL.

1,322,305.

Specification of Letters Patent.

Patented Nov. 18, 1919.

Application filed November 6, 1917. Serial No. 200,489.

To all whom it may concern:

Be it known that I, DAVID K. HUTCHCRAFT, a citizen of the United States, and a resident of Indianapolis, county of Marion, 5 and State of Indiana, have invented a certain new and useful Air-Lift-Pump Control; and I do hereby declare that the following is a full, clear, and exact description thereof, reference being had to the accompanying drawings, in which like letters refer to like parts.

In air lift pumps, for many purposes it is desirable to separate the air from the water at the top of the well by means of a 15 separating chamber, by which the pressure of the separated air is utilized to force the water on into an associated system. The accumulated air in this separating chamber must be allowed to escape as it accumulates, 20 so as to maintain the proper pressure and proper water level therein and the constant flow of water therefrom.

It is the object of this invention to provide an improved and novel means for controlling the escape of air and water from such 25 separating chamber, whereby a constant stream of air-free water is supplied or discharged therefrom to any associated system, and the invention relates more particularly 30 to means for controlling the escape of air from said separating chamber, which is accurately and sensitively controlled by the air pressure in the pump. This makes the action of said air escape control absolutely 35 accurate and sensitive, so that the air pressure in the separating chamber will be the same as that in the pump system substantially, and just enough air will escape from the separating head as to maintain a uniform 40 and desired air pressure in the separating chamber.

In this invention the air relief valve for the separating chamber, whereby a uniform pressure is maintained therein for the proper 45 discharge of water therefrom, is made dependent upon the air pressure in the pump system, and, in the form particularly here shown, in the air line. The air pressure in the air line may greatly vary. Thus, if several 50 pumps are supplied from one air control and some of those pumps be temporarily cut off, the air pressure in the air lines of the remaining pump or pumps would be immediately and greatly increased. If that increased pressure in the air line could not

control the air relief from the separating chamber, it would become choked with air so as to not operate satisfactorily. In the invention herein, an increased air pressure in the air line would cause an increased 60 opening in the air relief pressure in the separating chamber and a relief from any appreciable additional air pressure in the separating chamber. Likewise, the air pressure from the control varies. If it diminishes, 65 the reduced air pressure in the air line would cause a movement of the air relief valve correspondingly toward closing position. Hence, the ideal control of the air relief valve from the separating tank is that 70 which is dependent upon the air pressure in the air line or pump system.

The full nature of the invention will be understood from the accompanying drawings and the following description and 75 claims.

In the drawings, Figure 1 is a diagrammatic view showing a well having an air lift separator pump embodying my invention. Fig. 2 is an enlarged vertical section 80 of the separator and air escape controlling means. Fig. 3 is an enlarged section of the air escape controlling means.

At a suitable depth within the well casing 10 is located the air lift pump 11 of any 85 suitable type, which air lift pump receives water from within the well casing 10, and receives air from an air-supply pipe 12 supplied from a reservoir 13 in which the pressure is maintained by any suitable compressor 14. The mixture of air and water produced within the pump 11 rises in the eduction pipe 15 and is discharged into a separating chamber 16, the eduction pipe 15 preferably extending through the bottom of 90 the separating chamber and well up into it and being covered by a suitable umbrella or mushroom plate 17 with sides 17' overhanging the upper end of the eduction pipe 15 so as to deflect downward the water discharged from the eduction pipe 15 and allow the escape of the air from such water, the mushroom plate 17 and the perforations in the depending sides 17' assisting in the separation of air and water, and the perforations allowing the water to escape from within the perforated sides 17' more freely, 100 so as to steady the level of the water in the separating chamber 16. A water discharge pipe 18 projects into the chamber 16, pref. 105 110

erably through the bottom thereof and may be carried horizontally to any desired point and then turned upward to discharge into any suitable system, here a suitable reservoir 5 19, as clear from Fig. 1. The intake end of the water discharge pipe 18 within the casing 16 is located within a cylinder or bell 20 which at the bottom is provided with inlet 10 openings 21, preferably wider at the top than at the bottom, as shown in Fig. 2. A cut-off ring 22 has a sliding fit on the cylinder 20 and is carried by an annular float 23 surrounding such cylinder, so that such cut-off ring rises and falls with the water level within the casing 16 and closes to a greater or less degree 15 the openings 21 as the water level in such casing falls, so as to diminish the size of the outlet openings when the pressure above the water in the casing 16 (by which pressure 20 the water level is depressed) increases, thus tending to maintain the outflowing stream through the pipe 18 constant.

A hollow cylindrical air escape chamber 25 is mounted on the top of the separating chamber 16, having at its lower end an inlet port 26, which is in communication with the upper end of the chamber 16 which contains the air which has been separated from the water. The port 26 is closed and 25 controlled by valve 27 secured to the lower end of the valve rod 28 which is vertically movable through the nut 29, gland 30 and plate 31 which closes the upper end of the air escape chamber 25. The upper end of 30 the valve rod 28 is secured at its upper end to a piston 32 operating in a cylinder 33 which is secured upon the plate 31. In fact 35 the bolts 34 extend through flanges on said cylinder 33, air escape chamber 25 and the intermediate plate 31, whereby those three 40 parts are rigidly secured together. From the air escape chamber 25 there is an outlet 35 to the atmosphere or any place desired.

When the valve 27 is seated the piston 32 45 is held some distance above the plate 31 so as to leave an air chamber 36 into which air under pressure enters through the inlet 37 and pipe 38 leading from the air supply pipe 12 for the pump. The pipe 38 has in it a 50 cut-off valve 39. When there is weak air pressure or no air pressure in the chamber 36 the valve 27 will be held closed by the spring 40 in the cylinder 33 which is a spiral spring lying between the piston 32 and disk 55 41 at the top of the cylinder. A screw bolt 42 extends through the upper end of the cylinder 33 and has a lock nut 43 on it, whereby the tension of the spring 40 can be accurately adjusted. In the upper end of 60 the cylinder 33 there is an air vent 44.

From the foregoing description it is seen 65 that the air pressure from the pump line controls the air escape valve 27 by accurately balancing the pressure of the spring 40 on piston 32 with the desired or normal

air pressure in the pump line and in chamber 36, and valve 27 will be responsive to the air pressure in the pipe line. When that pressure increases above normal it will force the piston 32 upward and open the valve 70 27 and permit the air to escape from the separating chamber 16. As soon as the escape of air makes the pressure in the separating chamber normal, then the valve 27 will assume normal position. If the pressure 75 in the pipe line goes below normal, then the spring 40 will force the valve 27 closed. By accurately adjusting the tension of spring 40, therefore, this device can be made to perform its function with unusual accuracy and sensitiveness, and as a result of my arrangement, the stream of water discharged 80 from pipe 18 may be maintained substantially constant and substantially air free. Sometimes, however, the separation of the air from the water is not entirely complete 85 when the water enters through the slots 21, so that some air is carried with the water into the cylinder 20. This air, though small in amount, might separate from the water 90 within the cylinder 20, and collect at the top of such cylinder, and in the course of time might make the system "airbound". In order to prevent this, I provide a pet cock 50 which connects the space within the upper 95 end of the cylinder 20 with the atmosphere, so as to provide a restricted escape vent for any air which may collect. By proper adjustment of the pet cock 50, any air which collects in the cylinder 20 may be permitted 100 to escape while the vent is sufficiently restricted so as to prevent any material amount of water from passing through.

The invention claimed is:

1. An air lift separator pump including 105 an air lift pump having an air supply pipe, an eduction pipe, a separating chamber into which said eduction pipe discharges with an outlet at the upper end for the normal passage of air from said chamber, a water 110 outlet pipe leading from said chamber, a yieldingly closed valve for closing said outlet, and means actuated by the air pressure in said pump system for opening said valve.

2. An air lift separator pump including 115 an air lift pump having an air supply pipe, an eduction pipe, a separating chamber into which said eduction pipe discharges, a water outlet pipe leading from said chamber, an air outlet chamber in communication with 120 the upper end of the separating chamber for the normal passage of air from said separating chamber, a valve for controlling the outlet from the separating chamber to the air outlet chamber, and means mounted in 125 connection with said air outlet chamber controlled by the air pressure in the pump system for controlling said valve.

3. An air lift separator pump including 130 an air lift pump having an air supply pipe,

an eduction pipe, a separating chamber into which said eduction pipe discharges, a water outlet pipe leading from said chamber, a valve for controlling the normal passage 5 of air from the upper end of the separating chamber, an adjustable spring tending to hold said valve closed, and means adapted to be actuated by air under the pressure in said pump system for opposing the action 10 of the spring and opening the valve.

4. An air lift separator pump including an air lift pump having an air supply pipe, an eduction pipe, a separating chamber into which said eduction pipe discharges, a water outlet pipe leading from said chamber, and means controlled by the air pressure in the air supply pipe of the pump for controlling the escape of air from the upper end of said separating chamber.

20 5. An air lift separator pump including an air lift pump having an air supply pipe, an eduction pipe, a separating chamber into which said eduction pipe discharges, a water outlet pipe leading from said chamber, 25 means in said chamber for separating the air and water, and means controlled by the air pressure in the air supply pipe of the pump for controlling the escape of air from the upper end of said separating chamber.

30 6. An air lift separator pump including an air lift pump having an air supply pipe and an eduction pipe, a separating chamber into which said eduction pipe discharges having a normal air outlet at its upper end, 35 a water outlet pipe leading from said chamber, float controlled means for controlling the inlet of said water outlet pipe and movable toward open and closed positions upon rise and fall of the water level in said chamber, and means controlled by the air pressure in the air pump system for controlling the passage of air from the upper end of 40 said separating chamber.

7. An air lift separator pump including an air lift pump having an air supply pipe and an eduction pipe, a separating chamber into which said eduction pipe discharges, said chamber having an outlet for the air from the upper part thereof, a water outlet 50 pipe leading from said chamber, means for controlling the inlet to said water outlet pipe, a valve for controlling the escape of air from the upper end of said chamber, and means controlled by the air pressure in the 55 air supply pipe for controlling said valve.

8. An air lift separator pump including an air lift pump having an air supply pipe and an eduction pipe, a separating chamber into which said eduction pipe discharges, 60 said chamber having an outlet for the air from the upper part thereof, a water outlet leading from said chamber, means for controlling the inlet to said water outlet pipe, a valve for controlling the escape of air from 65 the upper end of said chamber, a spring

tending to hold said valve closed, and means adapted to be actuated by the air under pressure from said air supply pipe in opposition to the action of said spring for opening the valve.

9. An air lift separator pump including an air lift pump having an air supply pipe and an eduction pipe, a separating chamber into which said eduction pipe discharges, said chamber having an outlet for the air 70 from the upper part thereof, a water outlet pipe leading from said chamber, means for controlling the inlet to said water outlet pipe, a valve for controlling the escape of air from the upper end of said chamber, a rod 75 on said valve, a piston on said rod, a cylinder in which the piston operates, an air connection between said air supply pipe and the cylinder for actuating the piston and the valve, and a spring tending to close the 80 valve.

10. An air lift separator pump including an air lift pump having an air supply pipe and an eduction pipe, a separating chamber into which said eduction pipe discharges, 90 said chamber having an outlet for the air from the upper part thereof, a water outlet pipe leading from said chamber, means for controlling the inlet to said water outlet pipe, a valve for controlling the escape of 95 air from the upper end of said chamber, a rod on said valve, a piston on said rod, a cylinder in which the piston operates, an air connection between the air pump system and the cylinder for actuating the piston and the valve, a spring tending to close the valve, 100 and means for adjusting the tension of the spring.

11. An air lift separator pump including an air lift pump having an air supply pipe 105 and an eduction pipe, a separating chamber into which said eduction pipe discharges, said chamber having an outlet for the air from the upper part thereof, a water outlet pipe leading from said chamber, means for controlling the inlet to said water outlet pipe, a valve for controlling the escape of 110 water from the upper end of said chamber, a rod on said valve, a piston on said rod, a cylinder in which the piston operates, an air 115 connection between said air supply pipe and the cylinder for actuating the piston and the valve, a spiral spring in said cylinder with one end acting against said piston and air pressure for closing the valve, a disk in said 120 cylinder engaging the other end of said spring, and a set screw extending through the end of the cylinder for moving said disk to adjust the tension of the spring.

12. An air lift separator pump including 125 an air lift pump having an air supply pipe and an eduction pipe, a separating chamber into which said eduction pipe discharges, said separating chamber having an outlet for the normal passage of air from the up- 130

per part thereof, a water outlet pipe leading from said chamber, means for controlling the inlet to said outlet pipe, an air receiving chamber secured to the upper end of said separating chamber and having a port communicating with the outlet from said separating chamber and also an outlet opening for the escape of the air, a valve for closing the port communicating with the separating chamber for regulating the passage of air therefrom, and means controlled by air under pressure from the air pump system for controlling the operation of said valve.

13. An air lift separator pump including an air lift pump having an air supply pipe and an eduction pipe, a separating chamber into which said eduction pipe discharges, said separating chamber having an outlet for the escape of air from the upper part thereof, a water outlet pipe leading from said chamber, means for controlling the inlet to said outlet pipe, an air escape cham-

ber secured to the upper end of said separating chamber and having a port communicating with the outlet from said separating chamber and also an outlet opening for the escape of the air, a valve for closing the port communicating with the separating chamber for regulating the escape of air therefrom, a plate on said air escape chamber, a valve rod connected with said valve and extending through said plate, a cylinder secured to said plate, a piston secured to the outer end of said valve rod and operating in said cylinder, a spring in said cylinder acting on said piston to close the valve, and a connection extending from said air pump system to the end of said cylinder for actuating the piston against the influence of the spring and opening the valve.

In witness whereof, I have hereunto affixed my signature.

DAVID K. HUTCHCRAFT.
